[57] CLAIM

The ornamental design for a modular mail processing machine, as shown and described.

DESCRIPTION

FIG. 1 is a top, front and right side perspective view of a modular mail processing machine showing our new design;

FIG. 2 is a front elevational view thereof;

FIG. 3 is a top plan view thereof;

FIG. 4 is a right side elevational view thereof;

FIG. 5 is a left side elevational view thereof; and,

FIG. 6 is a rear side elevational view thereof.

FIG. 1

FIG. 2

FIG. 3

FIG. 4**FIG. 5**

FIG. 6
